UNITED STATES PATENT OFFICE.

DAVID SCHEIDECKER, OF FORT MORGAN, COLORADO.

TOOL FOR SPREADING BRIDLE-WIRE HOOKS.

1,237,391.

Specification of Letters Patent. Patented Aug. 21, 1917.

Application filed February 14, 1917. Serial No. 148,628.

To all whom it may concern:

Be it known that DAVID SCHEIDECKER, a citizen of the United States, residing at Fort Morgan, in the county of Morgan and State of Colorado, has invented certain new and useful Improvements in Tools for Spreading Bridle-Wire Hooks, of which the following is a specification, reference being had to the accompanying drawings.

10 This invention relates to tools for repairing or adjusting parts of piano actions, and particularly to a tool designed to spread or open the hook-like coil whereby a bridle wire is connected to the bridle strap on a piano action.

15 In practically all upright piano actions, the bridle wire is formed at its upper end as illustrated in Figure 5 by bending the wire in the form of a coil or hook, with the bill 20 of the hook bent so as to extend upward. The bridle tape or strap is disposed with its outer end through the loop or coil and with the upwardly extending bill passed through a perforation in the extremity of the tape.

25 It is very often necessary to put in new bridle straps, the old straps being liable to become worn or broken, or being eaten away by mice or moth. The bills of the loops or hooks are often initially so tightly closed 30 against the hook or loop that they must be opened up considerably or spread apart, that is the bills spread from the loop or body of the hook in order that the leather terminal of the bridle strap can be removed 35 from the bill and this is rendered all the more necessary because this leather terminal often becomes stiff. Furthermore tuners will often pinch together the bill and body 40 of the hook or loop so as to prevent the bridle strap from rattling against the loop or hook which often occurs when the bridle strap or the leather terminal end thereof becomes hard through age. When new bridle straps have to be inserted, which is 45 often the case, for the reasons above stated, it is very difficult with ordinary tools to open or spread the loop or bill from the body of the hook so as to remove the old strap and slip the new one in place. As far 50 as I know, this work has always been done by inserting a small chisel, screw driver, knife, or like tool, between the bill on the loop or body and then turning the instrument so as to spread the bill from the loop 55 and this is not only quite a task, but it is

very liable to twist or bend the bridle wires, which have afterward to be straightened.

It is the general object of my invention to provide a tool, therefore, which will expeditiously open these hooks of the bridle 60 wires so that the bridle straps may be readily removed therefrom and which will not bend the bridle wire and it is a further object of the invention to provide a tool in which the parts are adjustable so that the 65 bill may be shifted from the loop of the bridle hook any desired distance without any particular care being exercised by the operator.

A further object of the invention is to 70 provide a tool of this character comprising two relatively shiftable shanks, a handle rigidly connected to one of the shanks, and an operating handle pivotally connected to the rigid handle and operating to shift the 75 movable shank relative to the fixed shank with sufficient power to spread or bend apart the two portions of the bridie hook.

A further object of the invention is to 80 provide a device of this character which is very simple in construction, may be cheaply made, and is thoroughly efficient in action.

The invention is illustrated in the accompanying drawings, in which:

Fig. 1 is a side elevation of my improved 85 implement, the shank 11 being partly in section;

Fig. 2 is a top plan view of the implement shown in Fig. 1;

Fig. 3 is an underside view thereof; 90
Fig. 4 is a section on the line 4-4 of Fig. 1;

Fig. 5 is a fragmentary perspective view 95 of a bridle wire and tape;

Fig. 6 is a fragmentary perspective view 95 on a large scale of the bridle wire and tape and the end of my improved implement showing the manner of use;

Figs. 7 and 8 are fragmentary underside plan views of the forward end of the implement and a portion of the bridle wire showing the manner in which the loop or hook of the bridle wire is expanded; 100

Fig. 9 is an enlarged elevation of the bridle wire and hook showing an end view 105 of the shank 15 and a sectional view of the end of the shank 11;

Fig. 10 is a fragmentary elevation showing a portion of a piano action with the implement applied. 110

Referring to these drawings, it will be seen that my improved tool comprises a handle 10, from which extends an integral straight shank 11, the extremity of this shank being deflected as at 12 and reduced in width and thickness and pointed. In other words, the extremity of the shank has in plan view a somewhat lanceolate shape. The inner face of this deflected extension of the shank 11 is flat and adjacent to the end of this extension 11 there is formed the perforation 13. The shank is also formed with a plurality of ears 14, formed with rectangular alining passages in which a second shank 15 is disposed for longitudinal sliding movement. The shank 10 is also formed with a pair of ears 16 spaced from each other to receive between them the inner angularly bent end or nose 17 of a movable handle 18 which is pivoted to the ears 16, as at 19.

The shank 15 at its forward end has a flat face confronting the flat face of the extension 12 and closely adjacent thereto. The extremity 20 of the shank 15 is reduced in thickness, but its width is greater than the width of the extension 12 at its narrowest part. The terminal end of extension 20 of the shank 15 is formed with a longitudinally extending slit 21 which is in alinement with the perforation 13 in the portion 12. Disposed between the lugs 14 of the shank 11 is a coiled compression spring 22, which bears at its forward end against the forward lug 14 and at its rear end against a transverse pin 23. Thus the coiled compression spring urges the shank 15 rearward. The rear portion of the shank 15 is screw-threaded as at 24 and the rear extremity of the shank is flattened as at 25 and passes between the ears 16 and bears operatively against the face of the angular nose 17 of the handle 18. Thus it will be obvious that when the handle 18 is moved toward the handle shank 10 the shank 15 will be movable longitudinally outward against the face of the spring 22 and that when pressure is released on the handle 18, the spring 22 will shift the shank 15 rearward relative to the shank 11. For the purpose of limiting the outward movement of the shank 15 relative to the shank 11, I mount upon the screw-threaded portions 24 of the shank 15 the screw threaded stop or adjusting nut 26, this nut being held in its adjusted positions by means of a coiled compression spring 27 disposed around the screw threaded rear portion of the shank 15 and bearing at one end against the nut 26 and at the other end bearing against the forward faces of the ears 16. Preferably the nut 26 is formed with a central annular stud over which the forward end of the coil spring is disposed.

The manner in which this tool is used

is as follows and is illustrated in Figs. 5 to 7. The pointed end or bill *a* of the bridle wire A is passed through the perforation 13. The handle 18 is now drawn toward the handle 10 by contracting the hand and this forces the shank 15 forward. The slot 21 receives the lower portion of the bill *a* and the ends 28 of the extension 20 bear against the looped portion *b* of the bridle wire. As a consequence of the relative movement of the part 12 and the part 20, the bill *a* will be drawn in one direction and the loop *b* will be forced in the other direction, thus spreading the bill from the loop to the position shown in Fig. 7 which permits the ready disengagement of the bridle strap or tape from the bridle wire hook or loop, without in any way bending the bridle wire.

It will be seen that the respective movements of the loop *b* and bill *a* are entirely relative, or in other words, that the bill will be drawn outward while the body of the wire is pushed inward or held from movement so that the bridle wire will not be bent nor will the loop *b* be in any way deformed inasmuch as the two end faces 28 will bear against the oppositely disposed portions of the loop *b*. After a new bridle strap has been inserted on the hook or loop of the bridle wire, it is an easy matter to again close this loop, if desired, by the use of ordinary pincers.

It will, of course, be seen that by the use of a tool of this character, it is an easy matter to open or spread the loops or hooks of bridle wires so as to remove the bridle straps therefrom or to reapply new bridle straps and it will be obvious that a great saving of time is effected in this work by the use of this tool; thus for instance, where a person has an entire set of straps to put in a piano, 88 straps for instance, in an ordinary piano, and the hooks are all pinched tight, the use of this implement will save at least an hour of time besides leaving the wires unbent and undamaged. By adjusting the nut 26 it is possible to limit the relative movements of the shanks 11 and 15 and thus limit the degree of spreading of the bills of the hooks upon the bodies of the hooks. Thus the operator will not have to judge at each operation just how much to move the handle 18 but may set the instrument for his averaged work. On the other hand, it is of course obvious that the nut may be very quickly run back to permit a maximum opening of the hook, if desired.

While I have devised this tool with particular reference to opening or spreading the hooks of bridle wires, yet I do not wish to be limited to this use, as the device might be used for other purposes. Furthermore I do not wish to be limited to the exact

form of my invention, as it may be modified in many ways, without departing from the spirit thereof.

Attention may be called to the one feature of the invention which at first might appear to be of no importance, but which is of practical importance, namely that the extension 12 projects beyond the perforation 13 in actual practice about 1" and that the faces 28 extend on each side a distance equal to the diameter of the loop of the bridle wire. Thus when the hook of the bridle wire is opened there will be no chance for the instrument to slip downward and bend the wire or for the portions 20 to enter the loop.

Having thus described my invention, what I claim is:—

1. A tool of the character described having relatively movable parts, one part having a perforation for engagement with the bill of a bridle wire hook and the other part being longitudinally slotted inward from its end to accommodate the bill and permit it to move beyond the bill and engage with the looped body of the hook, and means whereby said parts may be relatively shifted and thereby displace the bill of the hook with respect to the body thereof.

2. In a tool of the character described, a shank having a perforation at one end for engagement with the bill of a bridle hook and having a handle at its opposite end, a second shank slidably mounted upon the first named shank for longitudinal movement therealong, the second named shank at one end being formed with a longitudinally extending open ended slit extending inward from the end of the shank and registering with said perforation, the slit being slightly wider than the perforation to permit the second named shank to accommodate the bill and move beyond the bill and engage with the looped body of the hook and a handle pivotally connected to the first named handle and operatively engaging the second named shank to shift it longitudinally relative to the first named shank.

3. In a tool of the character described, a shank having a perforation at one end for engagement with the bill of a bridle hook and having a handle at its opposite end, a second shank slidably mounted upon the first named shank for longitudinal movement therealong, the second named shank at one end being formed with a longitudinally extending open ended slit extending inward from the open end of the shank and registering with said perforation to accommodate the bill of the hook and permit the shank to move beyond the bill and engage with the looped body of the hook, a handle pivotally connected to the first named handle and operatively engaging the second named shank to shift it longitudinally rel-

ative to the first named shank, and a spring urging the second named shank to a retracted position.

4. A tool of the character described including a shank, having at one end a reduced extremity formed with a perforation, the shank being formed at its other end with a handle, and upon its inside face with ears, a second shank slidably mounted in said ears, the forward end of the second shank being formed with an inwardly extending slit alining with the perforation in the first shank, a spring urging the second named shank to a retracted position, and a handle pivotally mounted upon the first named shank and engaging with said second named shank to urge it to a projected position when the handle is contracted.

5. In a tool of the character described, a shank having a handle formed at one end and at the other end having a reduced portion provided with a perforation and with a flat inner face, the perforation extending at right angles to the flat face, the inner face of the shank inward of said reduced portion being formed with ears, a shank slidably mounted in said ears and having a flat inner face contacting with the inner face of the first named shank, the outer extremity of the second named shank being longitudinally slotted, the slit being in register with the perforation in the first named shank, a spring urging the second named shank rearward, and a handle lever angular in form pivotally mounted upon the first named handle and having its angular end bending against the rear end of the second named shank.

6. In a tool of the character described, a shank having a handle at one end and at its other end being formed with a perforation extending from its outer to its inner face, a shank confronting the inner face of the first named shank slidably mounted upon the first named shank and having at its outer end a longitudinally extending slit registering with the perforation, a spring urging the second named shank to a retracted position, a handle lever pivoted upon the first named shank and having an angular extension operatively bearing against the rear end of the second named shank, and adjustable means for limiting the outward movement of the second named shank.

7. In a tool of the character described, a shank having a perforation in its extremity adapted to receive the bill of a bridle hook and a coacting shank having an open-ended slit extending inward from its extremity and registering with the perforation and adapted to accommodate the bill of the hook and permit the shank to move past the bill, said shanks being relatively movable upon each other, a handle operatively

mounted upon one shank and operatively engaging the other shank whereby to shift the last named shank upon a movement of the handle, and means for adjustably limiting the movement of the slotted shank.

8. In a tool of the character described, a shank having a perforation at one end designed to receive the bill of a bridle hook and having a handle at its other end, a second shank slidably mounted on the first named shank for longitudinal movement therealong and formed at one end with a longitudinally extending open ended slit registering with the perforation in the first named shank and designed to accommodate the bill of the hook, but permit the end of

the slotted shank to move beyond the bill and engage the loop of the hook, a handle pivotally connected to the first named handle and operatively engaging the slotted shank to shift it longitudinally relative to the first named shank, a spring urging the second-named shank to a retracted position, and a stop having threaded engagement with a slotted shank and adjustably limiting its forward movement.

In testimony whereof I hereunto affix my signature in the presence of two witnesses.

DAVID SCHEIDEGGER.
